ABSTRACT

A *chrysanthemum* plant named 'Zanmudenali' characterized by its large sized blooms with white ray florets and prolific branching, and a response time of 7.5 weeks.

3 Drawing Sheets

1

Botanical designation: ***Chrysanthemum×morifolium*** Ramat.
Cultivar denomination: 'Zanmudenali'.

BACKGROUND OF THE INVENTION

The present invention relates to a new and distinct cultivar of *chrysanthemum* plant, botanically known as *Chrysanthemum×morifolium* Ramat., and hereinafter referred to by the cultivar denomination 'Zanmudenali'. 'Zanmudenali' is a product of a breeding and selection program for pot mums which had the objective of creating new cultivars with an anemone type inflorescence, a medium plant height and a response time of 7-8 weeks. 'Zanmudenali' is a seedling resulting from a cross of the female parent id 44258 and the male parent id 8967. Plants of the new cultivar 'Zanmudenali' differ from plants of the female parent in the following characteristics: (1) Inflorescence size. The inflorescences of the female parent are smaller than those of the seedling. And (2), Vigor. Plants of the female parent are less vigorous than those of the seedling. Plants of the new cultivar 'Zanmudenali' differ from plants of the male parent in plant vigor; the plants of the male parent are less vigorous.

The new and distinct cultivar was discovered and selected as a flowering plant within the progeny of the stated cross by Wilhelmus Bernardus Blom in a controlled environment (greenhouse) in Rijnsenhout, The Netherlands in April 2003. The first act of asexual production of 'Zanmudenali' was accomplished when vegetative cuttings were used from the initial selection in June 2003 and propagated further in a controlled environment in Rijnsenhout, The Netherlands. The new cultivar has been found to retain its distinctive characteristics through successive propagations, although the phenotype may somewhat vary with variations in environment such as light intensity and temperature.

BRIEF DESCRIPTION OF THE DRAWINGS

The present invention of a new and distinct variety of *chrysanthemum* is shown in the accompanying drawings, the color being as nearly true as possible with color photographs of this type.

2

FIG. 1 shows a plant of the cultivar in full bloom.
FIG. 2 shows the various stages of bloom of the new cultivar.

FIG. 3 shows the various stages of foliage of the new cultivar.

DESCRIPTION OF THE INVENTION

The observations and measurements were gathered in May 10 2010 from plants grown in a controlled environment (greenhouse) in Rijnsenhout, The Netherlands, in a photo-periodic controlled crop under conditions generally used in commercial practice. Three cuttings were planted in a pot with a diameter of 12 cm. The greenhouse temperatures for this crop 15 were at daytime 18.degree. C. to 25.degree. C., and at night about 20.degree. C. The photo-periodic response time in this crop was 7.5 weeks after an average of eight long days. After 20 this long day period growth retardants (Alar) were applied six times in an average dose of 1.5 gram/liter water until flowering. The plants were observed (directly) during the flowering of this crop. No tests were done on disease or insect resistance or susceptibility. No tests were done on cold or drought tolerance. To show the phenotype as described 'Zanmudenali' 25 can be planted without assimilation lighting (high pressure sodium lamps) between week 50 and week 40 of the next year under greenhouse conditions in The Netherlands. With assimilation lighting (minimum level 2500 lux) it can be planted all year round under greenhouse conditions in The Netherlands. 30 This new variety produces large sized blooms with white florets and a response time of 7.5 weeks.

From the cultivars known to inventor the most similar existing cultivar in comparison to 'Zanmudenali' is 'Letitia Time Improved' (U.S. Plant Pat. No. 18,359). When 'Letitia Time Improved' and 'Zanmudenali' are being compared the following difference is noticed: The difference of 'Letitia Time Improved' and 'Zanmudenali' are (1) Inflorescence type. And (2) Ray floret color. (1) The inflorescence type in 'Letitia Time Improved' is single, that of 'Zanmudenali' is anemone. (2) The ray-florets of 'Letitia Time Improved' are cream colored, while those of 'Zanmudenali' are white.

The following is a description of the plant and characteristics that distinguish 'Zanmudenali' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum xmorifolium</i> Ramat. 'Zanmudenali'		
Bud		
Size	Medium; cross-section 7 mm, height 6 mm	
Shape	Round	
Texture	Smooth	
Outside Color	Greyed-green 191A	
Phyllaries		
Number	26, arranged in 3 rows	
Shape	Elliptic	
Apex	Acute	
Base	Truncate	
Margin	Entire	
Color	Upper surface: Greyed-green 191A Lower surface: Greyed-green 191B	
Length and width	1-1.5 cm; 2 mm	
Texture	Pubescent	
Inflorescence		
Type	Anemone	
Height	2 cm	
Diameter	9 cm	
Peduncle length	2.5 cm	
Peduncle color	Green 139B	
Peduncle diameter	2 mm	
Peduncle texture	Pubescent	
Number per branch	Approx. 6 inflorescences	
Shelf life	4 weeks	
Seeds	Produced in small quantities, ovate, Greyed-brown 199A, length 1.5 mm, diameter 0.8 mm	
Fragrance	Faint <i>chrysanthemum</i> odor	
Color		
Center of inflorescence (disc florets)	Immature stage: Yellow-green 144C Mature stage: Green-yellow 1D	
Color of upper surface of the ray-florets	White 155D	
Color of the lower surface of the ray-florets	White 155D	
Tonality from Distance	A pot <i>mum</i> with large white flowers	
Color of the upper and lower surfaces of ray-florets after aging of the plant	White 155D	
Ray florets		
Texture	Upper and lower side smooth	
Number	76-80	
Shape	Elliptic	
Apex	Dentate	
Base	Attenuate	
Cross-section	Flat	
Longitudinal axis of majority	Twisted	
Length of corolla tube	0.4 cm	
Ray-floret margin	Entire	
Ray-floret length	3.5-4 cm	
Ray-floret width	2 cm	
Ratio length/width	Medium	
Disc florets		
Disc diameter	3 cm	
Distribution of disc florets	Abundant	

TABLE 1-continued

Botanical Description of <i>Chrysanthemum xmorifolium</i> Ramat. 'Zanmudenali'		
5	Shape	Funnel
	Color	White 155D at apex, Yellow 9D at base
	Length	1.2 cm
	Diameter	0.2 cm
	Receptacle	
10	Color	Yellow-green 145D
	Shape	Domed raised
	Height	5 mm
	Diameter	6 mm
	Reproductive Organs	
15	Androecium	Present on disc florets only
	Stamen length	3 mm
	Stamen color	Yellow-green 144A
	Anther color	Yellow 3A
20	Pollen	Present
	Pollen	Yellow 12A
	Gynoecium	Present on both ray and disc florets
	Style color	Yellow-green 154C
	Style Length	3 mm
	Stigma color	Yellow 7A
25	Stigma Width	1 mm
	Ovary	Enclosed in calyx
	Plant	
30	Form	Upright and free branching
	Growth rate	Medium
	Height	20 cm
	Width	30 cm
	Stem Color	Greyed-brown 199A
	Stem Strength	Strong
	Stem Brittleness	Not brittle
35	Stem Anthocyanin Coloration	Not observed
	Internode length	1-2 cm
	Length of lateral branch	From top to bottom 9 cm
	Lateral branch color	Green 137 C
	Lateral branch diameter	0.3 cm
	Lateral branch, attachment	Strong
40	Branching (average number of lateral branches)	Prolific with 4 breaks after pinching
	Response time	7.5 weeks
	Foliation	
45	Leaf color	Upper surface: Green 136A Lower surface: Green 138B
	Color midvein	Upper surface: Yellow-green 147D Lower surface: Yellow-green 148D
	Size	Medium; length 6-8.5 cm, width 3-5 cm
50	Quantity (number per lateral branch)	8-10
	Shape	Broadly elliptic
	Texture upper side	Sparsely pubescent
	Texture under side	Pubescent
55	Venation arrangement	Palmate
	Shape of the margin	Serrated
	Shape of Base of Sinus	Rounded
	Between Lateral Lobes	
	Margin of Sinus Between	Diverging
	Lateral Lobes	
60	Shape of Base	Asymmetric
	Apex	Mucronulate
	Petiole length	1-2 cm
	Petiole diameter	2 mm
	Petiole color	Yellow-green 147D
65

TABLE 2

Differences with the comparison variety when grown side-to-side		
	'Zanmudenali'	'Letitia Time Improved'
Inflorescence type	anemone	daisy
Ray floret color	White 155D	Green-yellow 1D

I claim:

1. A new and distinct *chrysanthemum* plant named 'Zanmudenali' as described and illustrated.
